E. D. Sornberger, INVENTOR
BY Victor J. Evans

ATTORNEY

UNITED STATES PATENT OFFICE

EARL D. SORNSBERGER, OF HARRISBURG, PENNSYLVANIA

OIL BURNER

Application filed April 17, 1929. Serial No. 355,892.

This invention relates to an oil burner, the general object of the invention being to provide a burner of simple construction and divided into three chambers by a pair of partitions, with means for introducing the oil adjacent the outer side of each partition, pilot burners for igniting the vaporized oil and means for introducing air into the center chamber and a deflector member at the top 10 which causes the flames to pass from the burner at each side thereof.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a top plan view of the device. 25 Figure 2 is a section on line 2—2 of Figure 1.

Figure 3 is a section on line 3—3 of Figure 1.

Figure 4 is a top plan view, with the cover 30 removed.

In these views, the numeral 1 indicates the body or bowl of the device which is preferably of rectangular shape at its top, with its bottom rounded and said bowl has a pair of upright partitions 2 therein which extend from end to end of the bowl and are spaced from the center, one at each side thereof. These partitions terminate an appreciable distance from the top of the bowl and each partition has a notch 3 at the center of its upper edge. The partitions divide the bowl into a center chamber and two side chambers. A longitudinal passage 4 is arranged in the bottom of the bowl, adjacent each partition and a slot 5 connects each passage with the interior of the bowl, the slot being arranged adjacent the outer wall of each partition. An oil pipe 6 is connected with these passages by the branch pipes 7 at one end of the device and the opposite ends of the passages are closed by

the screw plugs 8 so that the passages can be cleaned, when desired. A large air pipe 9 is in communication with the center chamber at the center thereof and a gas pipe 10 has the branches 11 connected with its inner end, the ends of these branch pipes being bent downwardly so as to ignite the oil vapors passing from the slots 5.

A substantially semi-circular cover member 12 has notched portions of its side edges engaging the notches 13 formed in the ends of the bowl at the upper edges thereof so that the ends of the cover overlap the ends of the bowl and the side edges of the cover project into the bowl. This cover member encloses that portion of the bowl which carries the partitions and leaves side portions at the top of the bowl open for the escape of the flames. A depending partition 14 is formed on the center part of the cover.

The oil will fill the passages 4 and overflow through the slots 5 into the bowl and after the walls of the bowl are heated, this oil will be vaporized and the vapors will be ignited by the pilot flames. The air from the pipe 9 will be deflected by the cover member 12 to both sides of the bowl, thus causing the air to mix with the vapors to insure proper combustion and the flames will pass from the spaces left by the cover member at each side of the bowl.

From the foregoing it will be seen that I have provided a simple and inexpensive form of burner which will produce an intense heat in the furnace or other device in which it is used.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. An oil burner of the class described comprising a bowl, a pair of upright partitions therein spaced from the center thereof, said bowl having passages in its bottom and a slot connecting each passage with the interior

of the bowl each slot being adjacent the outer side of a partition, a pilot burner for igniting the oil flowing from each slot, means for introducing air into the space between the two partitions and a cover member seated on the bowl above the parts thereof carrying the partitions and leaving spaces at the sides of the bowl.

2. An oil burner of the class described comprising a bowl, a pair of upright partitions therein spaced from the center thereof, said bowl having passages in its bottom and a slot connecting each passage with the interior of the bowl, each slot being adjacent the outer side of a partition, a pilot burner for igniting the oil flowing from each slot, means for introducing air into the space between the two partitions and a cover member seated on the bowl above the parts thereof carrying the partitions and leaving spaces at the sides of the bowl, said cover member being of substantially semi-cylindric shape and having a depending partition at its center.

3. An oil burner of the class described comprising a bowl of substantially trough shape, a pair of upright partitions in the bowl, each spaced from the center thereof, means for introducing air through the bottom of the bowl into the space between the partitions, means for introducing oil into the spaces adjacent the outer sides of the partitions, pilot burners extending into the oil receiving spaces and a removable cover member of semi-circular shape in cross section seated on the top of the bowl and covering the spaces thereof in which the partitions are arranged and leaving the sides of the bowl open at the top and a depending partition at the center of the cover.

40 In testimony whereof I affix my signature.
EARL D. SORNBERGER.
